WITNESS:

UNITED STATES PATENT OFFICE.

HOMER M. LAMB, OF WEST FRANKFORT, ILLINOIS, ASSIGNOR OF ONE-THIRD TO LOUIS KLEIN AND ONE-THIRD TO GEORGE B. GREENBAUM, BOTH OF FRANKFORT, ILLINOIS.

SANITARY CLOTHES-LOCKER.

1,378,802.

Specification of Letters Patent. Patented May 17, 1921.

Application filed August 9, 1920. Serial No. 402,419.

To all whom it may concern:

Be it known that I, HOMER M. LAMB, a citizen of the United States, residing at West Frankfort, in the county of Franklin 5 and State of Illinois, have invented new and useful Improvements in Sanitary Clothes-Lockers, of which the following is a specification.

An object of this invention is to produce 10 a sanitary clothes locker which shall be practically thief proof.

An object is to produce an elevated reticulated locker that will occupy comparatively small floor space, and being elevated will 15 permit of the attendant observing the person using the same, while being reticulated permits of the free circulation of air therethrough so that the clothes therein can be quickly dried.

20 A further object is to produce a locker which is elevated higher than the height of an ordinary person, and which comprises a substantially rectangular box-like body constructed of wire mesh or the like and in 25 which the door therefor is located at the bottom thereof, the standard on which the locker is supported being provided with hooks for holding clothes during the changing of garments by the user, while on the 30 standard is a slide having additional means for supporting clothes as well as a seat for the reception of the user in changing his clothes, the said slide being also provided with means whereby the same may be locked 35 in the locker when the slide is elevated and with additional means for locking the door thereto when the said slide is in its elevated and locked position.

The foregoing objects, and others which 40 will appear as the nature of the invention is better understood, may be accomplished by the construction, combination and operative arrangement of parts, such as is disclosed by the drawings.

45 In the drawings:

Figure 1 is a front elevation of the improvement with the slide in its lowered position.

Fig. 2 is a side elevation of the same.

50 Fig. 3 is a sectional view, approximately on the line 3-3 of Fig. 1, with the slide elevated and the door locked.

Fig. 4 is a sectional view approximately on the line 4-4 of Fig. 3.

Fig. 5 is a perspective view of the slide, 55 with the elements attached thereto, such as the clothes hanger support and the seat, removed.

Fig. 6 is a perspective view of the support. 60

Fig. 7 is a fragmentary top plan view of the inner end portion of the locker.

Fig. 8 is a transverse sectional view through the T-iron and the spaced bars 65 that engage therewith.

Preferably, but not necessarily the support of the improved locker is in the nature of two spaced bars 1-1, which have their ends offset to provide feet 2 that have means passing therethrough for securing the bars 70 to the floor, and to the ceiling of the room in which the locker is located. The bars 1-1 thus provide the standard for the construction, and the locker 3 is connected in any desired manner to the standard. The 75

locker is in the nature of a rectangular member, constituting frames that have facings of spring wire mesh, the said locker being closed on all of its faces except its bottom. On the lower corners of the locker 80 are outstanding studs 4. These studs pass through elongated slots 5 in the sides of the bottom frame 6. The bottom frame is of a size to snugly close the locker when moved thereunder. The bottom frame is 85 really in the nature of the door for the locker, and when in open position is slid on the studs 4 and arranged angularly with respect to the outer face of the locker, as illustrated in Fig. 2 of the drawings. The 90 bottom frame is provided with a hook 7 designed to engage a lug 8 on one side of the locker for holding the frame in its said angular position and the bottom of the locker open. Of course two hooks may be 95 employed on the door that provides the bottom 6 and in which instance two lugs are provided upon the locker. By reference to the drawings it will be noted that the central portion of the locker is formed with 100 a substantially rectangular channel portion to receive therein the standard, and the door, which constitutes the bottom 6, is likewise provided with a small depression.

Arranged for slidable movement between 105 the bars 1-1, that constitute the standard, is a plate 9. The plate 9 preferably has its rear end flanged as at 10, and this, it will be

noted, with the plate is in reality a T-iron. On the outer edge of the central rib of the T-iron, adjacent to the upper portion thereof there is an outstanding rod 11. On this 5 rod are hooks 12, a clothes hanger 13 and a shoe support 14. Adjacent to the bottom end the slideable plate 9 may be provided with a handle 15, whereby the same may be manipulated. Above the handle there is a 10 horizontally disposed seat 16, angle braces 17 being arranged between the bottom of the seat and the slide.

When the device is arranged against a 15 wall, the wall itself prevents the T-iron that constitutes the slide from moving rearwardly against the bars 1—1 that constitute the standard, but when the locker is positioned away from a wall, suitable means is 20 employed for preventing the rearward movement of the slide through the members constituting the standard. As a matter of fact, the rod 11 and the seat 16 will hold the rib of the slide properly between the plates constituting the standard.

25 The bars 1, comprising the standard, at the portion thereof within the locker 3 have a pivoted bolt 18 and keeper 19 therefor. The plate 9, which provides the central rib of the slide has an outstanding lug 20 which 30 rests on the bolt 18 when the latter is moved to engagement with its keeper. In addition to this, if desired, the inner end of the door that comprises the bottom 6 may be received in a notch in the said slide. The bottom 35 which constitutes the door 6 is provided with a depending apertured lug 21. Suspended by a flexible element 22 on the standard is a bar 24 that is designed to be passed through an opening 25 in a lug 26 on the slide. The 40 bar 24 is designed to pass through openings in the lugs 26 and 21, and to have the hasp of the lock 27 pass through the opening 25 in the said bar to prevent the withdrawal thereof by unauthorized persons, so that the 45 locker can be only opened by the owner thereof.

It is believed that the foregoing description, when taken in connection with the 50 drawings will amply set forth the construction and the advantages of my improvement without further detailed description.

What I claim is:

1. An elevated locker having an open bottom and a slideable door for closing the bottom, and means for locking the door.
2. An elevated locker having a slideable door for closing the bottom thereof, means for locking the door in closed position, and means for latching the door in open position.

3. An elevated reticulated locker having 60 an open bottom, a slideable and tiltable door for closing the bottom, means for locking the door in closed position, and means for sustaining the door tilted when in open position.

4. A reticulated elevated locker having an 65 open bottom and a slideable and tiltable door for closing the bottom, means for sustaining the door tilted in open position, a standard supporting the locker, a slide vertically movable on the standard and having clothes 70 supporting means which are designed to be moved downwardly below the locker when the door thereof is in open position, and which, when moved in an opposite direction are designed to be fully received in the 75 locker, means between the standard and slide arranged in the locker for holding the slide in its last mentioned position, and means for locking the door of the locker when the same is in closed position.

5. A reticulated locker having an open bottom, a door having its sides slotted and engaged by studs on the lower corners of the locker, means for supporting the door at an inclination with respect to the locker when 80 in open position, a standard supporting the locker elevated, a slide movable through the standard, a horizontal seat arranged transversely on the slide, a rod on the slide having article supporting means thereon, means for 85 locking the slide to the standard when the latter is moved to bring its article supporting means into the locker, and means for locking the door to the slide when the latter is in its last mentioned position.

6. A reticulated locker having an open bottom, a standard comprising two spaced members to which the locker is secured, a slideable and tiltable door for closing the open bottom of the locker, means for sustaining the door in open position, a cross sectionally T-shaped plate slideable between the spaced members constituting the standard, article sustaining means carried by the slideable plate and received in the locker when 100 the slideable plate is elevated, and arranged below the said locker when the door of the latter is opened and the slide is moved downwardly, and a lug on the slide, a swinging bolt carried by the standards and arranged in the locker designed to engage beneath the lug and hold the slide elevated and the article sustaining means in the locker, and means between the door of the locker and the standard for locking the former to 115 the latter when the door is in closed position.

In testimony whereof I affix my signature.
HOMER M. LAMB.
